(57) **CLAIM**

The ornamental design for an infant crawler, as shown and described.

DESCRIPTION

FIG. 1 is a perspective front view of an infant crawler, showing our new design.

FIG. 2 is a right side elevational view thereof.

FIG. 3 is a left side elevational view thereof.

FIG. 4 is a front elevational view thereof.

FIG. 5 is a rear elevational view thereof.

FIG. 6 is a bottom view thereof; and,

FIG. 7 is a top view thereof.

The broken line showing of the infant in FIG. 1 is for illustrative purposes and forms no part of the claimed design.

1 Claim, 5 Drawing Sheets

FIG. 2

FIG. 3

FIG. 5

FIG. 4

FIG. 7

FIG. 6
